[57] CLAIM

The ornamental design for a fabric covered doll, as shown and described.

DESCRIPTION

FIG. 1 is a top front and left side perspective view of a fabric covered doll showing my new design;

FIG. 2 is a front elevation view thereof;

FIG. 3 is a rear elevation view thereof;

FIG. 4 is a top plan view thereof;

FIG. 5 is a bottom plan view thereof; and

FIG. 6 is a right side elevation of the fabric covered doll, the left side elevation is a mirror image thereto;

FIG. 7 is a fragmentary right side elevation showing the upper portion of the fabric covered doll with the face cover and hood shown in the open position,

FIG. 8 is a top front and left side perspective view of the fabric covered doll shown with the face cover in the partially removed (open) position;

FIG. 9 is a view similar to FIG. 8, with the face cover fully removed to expose the face of the doll; and,

FIG. 10 is a view similar to FIG. 9, and also with the hood removed to fully expose the head of the doll.

The portions of the fabric covered doll that are not shown in the drawings do not form part of the claimed design.
